UNITED STATES PATENT OFFICE.

BERNARD D. WILLIS, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE-EXCHANGE SYSTEM.

Application filed November 29, 1909. Serial No. 530,399.

My invention relates to telephone systems in general, but more particularly to automatic or semi-automatic telephone exchange systems of that particular type in which 5 selectors and connectors are employed, and more especially to systems of this kind in which no operating grounds are employed at the substations, and in which the electric current for talking purposes is supplied to 10 the lines from one or more batteries at the exchange or central station.

Generally stated the object of my invention is the provision of an improved system wherein the actuating or propelling 15 magnets of certain switches, such, for example, as the second selectors and connectors, are controlled by the relay or relays of the first selector, rather than by relays which are individual to the said second 20 selectors and connectors.

A special object of my invention is the provision of a system of this kind in which the current for talking purposes is supplied to the calling line through the first selector 25 and to the called line through the connector—that is to say, a system in which there are bridging coils in the first selectors for supplying talking current to the calling lines, and in which there are bridging coils 30 in the connectors for feeding talking current to the called lines.

Another object is the provision of a system of this kind in which the relay or relays 35 of the first selector control the other switches, such as the second selector and the connector, when the call is from one line to another line in the same exchange, so that no relays are necessary for the connectors that are required for giving service between 40 subscribers of the same exchange, but in which connectors with line relays are employed for extending calls from one exchange to the other, whereby connectors without relays are available for local calls; 45 and connectors having line relays are available for service between the two exchanges, or between a main exchange and a subexchange, in which case the connectors with relays would be located at the subexchange.

50 Another object of my invention is the provision of a system of this kind in which the first selectors are controlled over metallic circuits, and in which the relays of the first selectors are capable of controlling the other

switches, such as the second selectors and 55 the connectors, over grounded line circuits, as by grounding first one side and then the other of a trunk line, which is a distinguishing feature of what is commonly known as a 60 three-wire system.

To the foregoing and other useful ends my invention consists in matters hereinafter set forth and claimed.

In the accompanying drawings Figures 1 and 2 are a diagram of the circuits and apparatus for connecting a calling subscriber 65 A of a first exchange with a called subscriber A' of a second exchange in a system embodying the principles of my invention.

In Fig. 1 the line of the calling subscriber 70 terminates in the line switch C belonging to a group controlled by the master switch D. As shown, the calling line has been extended through the first selector E and 75 through the second selector F.

Fig. 2 is a similar view representing circuits and apparatus of the second exchange, and showing a continuation of the circuit from the second selector (Fig. 1) through the connector H and the line switch C' to the called subscriber A'. The switch C' is 80 similar to the switch C, and the substation A' of the second exchange is also similar to the substation A.

At I (Fig. 2) is shown a ringer generator, 85 at J a busy-signaling machine, at K a ringer interrupter and at B a battery with its positive terminal preferably grounded at G. It will be noted that the battery lead 80 is common to both exchanges. This is 90 not necessary, however, as another battery might be provided in Figs. 1 and 3 with its positive terminal preferably grounded, and the common connecting battery lead 80 might then be omitted.

Fig. 3 is a diagrammatic representation of a connector similar to the connector H located, however, at the first exchange, and is used for making local calls in that exchange, as from subscriber A to some other subscriber, similar to A', whose line terminates in a line switch similar to the line switch C' but located at the first exchange.

The substation A (Fig. 1) is an automatic substation adapted and simplified to work in connection with a two-conductor automatic system having no ground connection at the substation for calling purposes. It com-

prises a receiver 2, induction coil 3, transmitter 4, switch hook 5, ringer 6, and an impulse wheel 7 carrying on its periphery the impulse teeth 8 for operating the impulse springs 9 and 10. The impulse wheel 7, together with a dial (not shown), is rigidly secured to the shaft 11. When the switch hook is in its normal position the ringer 6 in series with the condenser 12 is bridged across the line conductors 13 and 14.

The line switch C may be of any suitable or approved type. It may be a modified form of the line switch disclosed in British Patent No. 26,301 of 1906, and similar to that described in the American Telephone Journal of Chicago, Illinois, of June 6, 1908. In its general form it comprises a trip magnet 17, a release magnet 26 and a bridge-cut-off relay 27. The trip magnet is designed to operate the usual plunger for pressing the bank springs 18 and 19, 20 and 21, 22 and 23 and 24 and 25 (of which there are a number of similar sets) into engagement. This plunger is so arranged that when in normal position it is under the control of the master switch D, whereby the said plunger may always be removed from opposite a seized trunk to a position opposite an idle trunk. The release magnet operates to restore the plunger to normal position. The bridge-cut-off relay 27 operates to shift the springs 74 and 77 out of engagement with the springs 73 and 78, respectively.

The master switch D may be of any suitable or approved type, for instance of the general type described and illustrated in the said American Telephone Journal of Chicago, Illinois, of June 6, 1908. Its bank O comprises the individual segments *a* (one for each set of line switch bank springs) and the common segment 34. The master switch controls the plungers of several line switches, usually one hundred, holding them always in readiness to engage an idle trunk terminal. This particular master switch shaft is given a step-by-step reciprocating motion, and all idle plungers are held in locking engagement with said shaft. The plungers of the line switches are not self-aligning—that is, a plunger does not automatically come into locked engagement with the shaft until the master switch shaft again resumes the original position where the plunger was tripped. When one line switch operates, its plunger is tripped and engages the springs of the bank terminals of an idle trunk. The motor magnet relay 31 is accordingly energized. This relay operates to close the motor magnet circuit and the circuit of the relay 33. The motor magnet operates to rotate the ratchet wheel and fibre interrupter wheel. When the ratchet wheel is operated one notch the interrupter wheel has rotated enough to close the springs 91 and 92, which keep the motor magnet operating until the idle plunger

ers are directly opposite the bank terminals of an idle trunk. When this position is reached the springs 91 and 92 separate, and as the master switch wiper 35 has been moved to a position on the master switch bank corresponding to the idle trunk, the motor magnet is deenergized. While the motor magnet is operating the relay 33 is energized, thereby shifting the spring 79 out of engagement with the spring 81 and into engagement with the spring 92. In this way all the trip magnets are disconnected from the battery lead and connected to a busy-signaling current similar to the busy-signaling current furnished by the apparatus J in Fig. 2, thus preventing the selection of a busy trunk and giving a subscriber the busy signal if all the trunks are busy.

The first selector E is of the general type disclosed in United States Letters Patent to Keith, Erickson and Erickson, No. 815,321, granted March 13, 1906, but modified to operate in conjunction with a two-wire system. One of the improved features of this selector over the usual first selector of this type, used in the said two-wire system, is that the operations of the succeeding switches in a connection are controlled by relays of the switch E. The first selector switch E embodies the following devices: The wipers 36, 37 and 38 which are secured to a shaft (not shown) which has a vertical motion controlled by the vertical magnet 39 and a rotary motion controlled by the rotary magnet 40. The side switch, comprising the wipers 41, 42, 43 and 44, is controlled by the private magnet 45. The operation of the switch is under the control of the subscriber through the medium of the relays 46, 47 and 48. A release magnet 49 is provided for restoring the switch to its normal position when the calling subscriber hangs up his receiver.

The second selector F is of the general type as the first selector E, but has no line relays. It is operated by the subscriber through the medium of the relays of the first selector switch E. The switch F, as here shown, comprises the usual shaft wipers 50, 51 and 52, side switch comprising the wipers 53, 54, 55 and 56, vertical magnet 57, rotary magnet 58, private magnet 59, release magnet 60 and release relay 61. The connector H is of the general type disclosed in United States Letters Patent No. 815,176, granted March 13, 1906, to Keith, Erickson and Erickson; but, like the second selector F, is adapted for two-wire work and is operated through the medium of the relays of the first selector E. After the connection has been extended from the calling substation through the selector switches E and F to the connector H, impulses from said substation are repeated by the relay 46 (Fig. 1) to the relay 62 (Fig. 2). Each time the re-

5 lay 62 energizes, while the side switch is in first position, the vertical magnet 63 is energized to raise the shaft of the connector H, together with the wipers 64, 65 and 66, one step. When the side switch is in second position the energization of relay 62 results in energizing the rotary magnet 67 to step the shaft and its wipers around. The relay 68 is operated through the medium 10 of the relay 48 of the selector switch E, the relay 68 in turn controlling the operation of the private magnet 69 which governs the side switch. The double-wound relay 70 energizes when the called subscriber answers and operates to open the circuit of the ringer relay 71 and to energize the relay 72 which locks and maintains the circuit of the ringer relay open until the connector H is released, thus preventing the bell of the 15 called substation from being rung when the subscriber at that substation hangs up his receiver before the receiver at the calling substation is restored to the switch hook. As soon as the connector H completes connection with the desired line the ringer relay 71 begins to be intermittently energized through the medium of the interrupter K. This continues until the called subscriber answers, when the circuit of ringer relay is 20 opened as above mentioned. When the ringer relay is energized it opens the line connection and bridges the ringer generator I across that portion of the line leading to the called substation.

25 In order to give a clear understanding of the operation of the system I will now explain how the subscriber at substation A may operate the exchange switches to obtain a connection with the substation A', whose number will be assumed to be 2220. When the receiver is removed from the switch hook at substation A (#5000) an energizing circuit is closed through the trip magnet 17 of the line switch C, causing the 30 said magnet to attract its armature and allow the plunger to be thrust into a bank of contacts containing the terminals of a trunk leading to a first selector E. The energizing circuit for the trip magnet 17 extends from ground G' through springs 78 and 77, line conductor 14, switch hook springs 76 and 75, impulse springs 19 and 9, primary winding 15 of induction coil 3, transmitter 4, line conductor 13, springs 74 and 73, trip magnet 17, springs 79 and 81 to the battery lead 80, thence through battery B to ground G. When the line switch plunger is thrust into the bank the springs 35 and 20 and 21, 22 and 23 and 24 and 25 are pressed into contact in pairs, as indicated. The engagement of springs 24 and 25 furnishes a guarding potential from ground G² to the normal conductor 82 for protecting the line of substation A 40 against seizure. The engagement of springs 24 and 25 also furnishes an energizing circuit for the cut-off relay 27 of the line switch, whereby the springs 74 and 77 are separated from the springs 73 and 78, thus cutting off the ground G² and trip magnet 70 45 17 from the line conductors 13 and 14. The energizing circuit of the relay 27 extends from ground G² through springs 24 and 25 and relay 27 to the battery lead 80, thence through battery B to ground G. The engagement of springs 22 and 23 closes a circuit extending from ground G³ through the motor magnet relay 31 of the master switch D to the common segment 34, thence over wiper 35 to contact 83 upon which it is assumed the wiper 35 is at this time resting, thence over conductor 84 and through springs 23 and 22 and magnet 26 to battery lead 80. Upon the closure of this circuit the relay 31 operates to force the springs 85 and 86 into engagement, but the release magnet 26 does not energize because its resistance is low compared with that of the relay 31. The closure of springs 85 and 86 energizes the motor magnet 32 in 50 multiple with the relay 33 over a circuit extending from ground at the points G⁴ and G⁵, through said magnet and relay in parallel, through interrupter springs 88 and 87 and springs 85 and 86 to the battery lead 80, thence through the battery B to ground G. The motor magnet 32 attracts its armature 89, which brings the pawl 90 into engagement with the ratchet wheel 29, thereby 55 moving it one step. When the said ratchet wheel is moved one step the spring 91, which rests normally at the bottom of a tooth of the wheel 30, is forced upward and into engagement with the spring 92, whereby the circuit through the motor magnet 32 is maintained, regardless of the springs 85 and 86. The motor magnet 32, being provided with the interrupter springs, now continues to operate like a buzzer to rotate the ratchet wheel 29 and the toothed wheel 30 until the 60 spring 91 drops down into the next notch. By this time the plunger shaft will have advanced all the plungers which are in locked engagement with it to the next trunk, and the wiper 35 will have left the contact 83, allowing the relay 31 to deenergize and motor magnet 32 to stop. If the next trunk is busy, however, the wiper 35 will find a 65 guarding potential on the next contact, the relay 31 will be again energized, and the motor magnet will continue to rotate the ratchet wheel 29 and plunger shaft until the wiper 35 finds an idle contact. The relay 33, which was energized simultaneously with the motor magnet, is slow-acting and does not deenergize again until the motor magnet has ceased operating. In its operated condition the relay 33 shifts the spring 79 from engagement with the spring 81 into the engagement with the spring 202, thereby 70 cutting off the ground G² and trip magnet 70 75 80 85 90 95 100 105 110 115 120 125 130

ting off the battery lead from all the trip magnets of all the line switches to which the master switch D is allotted. This is provided so that no line switch may be operated while its plunger is being moved by the master switch. The spring 202 of the relay 33 is connected with a busy-signaling machine so that any subscriber who tries to make a call while his master switch is 10 operating will receive the busy signal.

As soon as the connection is extended from the line conductors 13 and 14 to the selector E through the springs 18 and 19 and 20 and 21, the relay 46 is energized. The energizing circuit for the relay 46 extends from ground G⁶ through the winding 93 of said relay, through springs 21 and 20 to the line conductor 14, thence through substation A, line conductor 13, springs 18 and 19 and winding 204 of the relay 46 to the battery lead. The relay 46 upon energizing shifts the spring 96 out of contact with the spring 94 and into contact with the spring 97, whereby the slow-acting relays 47 and 48 are energized. The energizing circuit of the relay 47 extends from ground G⁷ through the relay 47 and springs 97 and 96 to the battery lead 80, thence through battery B to ground G. The circuit through the relay 48 extends 30 from ground G⁸ through the relay 48, spring 98, contact 99 and springs 97 and 96 to the battery lead 80. The relay 47 upon energizing removes a ground from the release magnet 49, and connects the impulse spring 109 through the springs 100 and 101 to the vertical magnet 39. In its energized condition the relay 48 maintains the circuit through the switch E open at points between the springs 103 and 104 and 105 and 106. The 35 engagement of the springs 107 and 103 closes a circuit from ground G¹⁰ through the springs 107 and 103, side switch wiper 41 in first position, contact 108 and private magnet 45 to the battery lead 80, whereby the private magnet is energized preparatory 40 to releasing the side switch to second position. The switch E is now in position for receiving impulses for the first digit of the number to be called.

55 As the dial at substation A returns to normal after being operated for the first digit (2), the impulse teeth 8 separate the springs 9 and 10 twice, allowing the relay 46 to deenergize a like number of times. Each time the relay 46 deenergizes, the 60 springs 109 and 95 close a circuit through the vertical magnet 39, while the circuit through the relay 47 is opened between the springs 96 and 97. The relay 47, however, is slow-acting and does not have time to deenergize while the springs 96 and 97 are separated. Each time the springs 95 and 109 engage, the vertical magnet is energized over a circuit extending 65 from ground G²⁶ through springs 95 and

109, springs 100 and 101, conductor 113, side switch wiper 42, contact 112, vertical magnet 39 to the battery lead, thence through battery B to ground G. The vertical magnet is energized twice over this circuit and 70 operates to raise the shaft wipers 36, 37 and 38 two steps to a point opposite the second bank level. As soon as the switch shaft is raised the first step the circuit formerly traced through relay 48 is broken at a point 75 between contact point 99 and spring 98, but said relay 48 receives an energizing impulse each time and relay 46 deenergizes through springs 96 and 94 and contact 114, which is now in engagement with the 80 spring 98. The relay 48 being slow-acting does not allow its armature to restore to normal between impulses. As soon as the impulses cease, however, the relay 46 resumes its energized position, and the circuit through the relay 48 is permanently opened by the separation of springs 96 and 94. The relay 48 now has time to deenergize and open the circuit of the private magnet 45 at a point between the springs 107 and 103. The private magnet thereupon deenergizes 85 and allows the side switch to pass to second position, the wipers engaging their second-position contact points. When the side switch wipers 41 and 42 leave their contact 90 points of the first position they break the connection normally existing between the private magnet 45 and conductor 115, and between the vertical magnet 39 and conductor 116. The side switch wiper 44, in its 95 second position, closes a circuit from ground G¹¹ through the rotary magnet 40 and interrupter springs 117 to the battery lead 80, thence through battery B to ground G. The rotary magnet thereupon energizes 100 and rotates the shaft wipers one step onto the terminals of the first trunk of the second level. If this trunk is not busy the side switch will be immediately tripped to third position by the action of the rotary 105 armature; but if the first trunk is busy the private wiper 38 will find the first contact grounded. When the private wiper engages the contact of a guarded trunk the 110 private magnet 45 is energized over a circuit extending from said grounded contact through side switch wiper 43, private magnet 45 to the battery lead 80. The private magnet 45 upon energizing locks the side switch in second position and the rotary magnet is again energized as soon as the 115 interrupter springs 117 come into contact. The rotary magnet will continue to rotate the shaft until the private wiper finds an unguarded contact, whereupon the private magnet circuit is broken, deenergizing it and releasing the side switch to third position, thereby opening the energizing circuit 120 of the rotary magnet 40 at the wiper 44. The side switch wipers 41 and 42, in the 125 130

third position, extend the lines of substation A through the shaft wipers 36 and 37 to the second selector F. When the wiper 43 engages the third-position contact a 5 guarding potential is supplied from ground G^{12} to the private wiper 38, thence to the corresponding private bank contacts of all the first selectors having access to the second selector F. The side switch wiper 43, in 10 third position, also closes an energizing circuit from ground G^{12} through said wiper 43, shaft wiper 38 and release relay 61. The relay 61 upon energizing separates the springs 118 and 119, thereby maintaining 15 the circuit of the release magnet 60 open, which would otherwise be closed as soon as the switch shaft is raised one step and spring 120 permitted to engage with contact point 121.

20 Now when the dial at substation A is operated for the second digit (2) the relay 46 is deenergized twice, as before, but the switch F is now under the control of said relay 46 and is operated to extend the connection through to a connector H. Each time the relay 46 deenergizes a circuit is 25 closed from ground G^{26} through springs 95 and 109, springs 100 and 101, side switch wiper 42, shaft wiper 37, side switch wiper 34 of the switch F and vertical magnet 57 to battery lead 80. The vertical magnet is 30 energized twice over this circuit, and operates to raise the shaft and shaft wipers 50, 51 and 52 two steps. Each time the relay 35 46 deenergizes an energizing circuit is also closed through the relay 48. This circuit extends from ground G^8 through said relay 48, spring 98, contact point 114 and springs 94 and 96 to battery lead 80, thence through 40 battery B to ground G. The relay 48 energizes upon the first impulse and remains energized until all the impulses are completed. In this case, however, the engagement of springs 107 and 103 closes an energizing circuit for the private magnet 59 of 45 the second selector F. This circuit extends from ground G^{10} through springs 107 and 103, conductor 115, side switch wiper 41, shaft wiper 36, side switch wiper 53 and 50 private magnet 59 to the battery lead 80, thence through battery B to ground G. After the impulses cease, and relay 48 again has time to deenergize, the circuit through 55 the private magnet 59 is opened and the side switch of the second selector released to second position. With the side switch in second position the wiper 56 closes an energizing circuit from ground G^{15} through the rotary magnet 58 to the battery B, said circuit including the interrupter springs 122. As soon as this circuit is closed the rotary magnet operates once to rotate the shaft wipers onto the contacts of the first trunk 60 of the second bank level, opposite which the said wipers were placed by the vertical mag- net. If this trunk is busy, however, the private wiper 52 finds a guarding potential present on the private contact which it engages, thereby closing an energizing circuit through the private magnet 59. This circuit extends 65 from said grounded contact through private wiper 52, side switch wiper 55 and private magnet 59 to the battery lead 80. The private magnet 59 upon energizing locks the side switch in second position and thus maintains the circuit through the rotary magnet 58. The rotary magnet will continue to rotate the shaft until the private wiper 52 reaches a non-grounded contact indicating an idle trunk, whereupon the private magnet 70 deenergizes and releases the side switch to third position. As soon as the side switch wiper 56 leaves the second-position contact the energizing circuit of the rotary magnet 75 is broken. The wipers 53 and 54, in third position, extend the connection through the switch F to the shaft wipers 50 and 51, thence over conductors 123 and 124 to connector H. The side switch wiper 55, in 80 third position, supplies guarding potential 85 from ground G^{16} to private wiper 52, thence to all the private bank contacts of the seized trunk in order to protect it against seizure by any other second selector. The side switch wiper 55, in third position, also closes 90 an energizing circuit for the release relay 179 of the connector H. This circuit extends from ground G^{16} , side switch wiper 55, shaft wiper 52, conductor 191 and relay 179 to battery lead 80, thence through battery 95 B to ground G. The lay 179 upon energizing separates springs 180 and 181 to maintain the circuit of the release magnet 100 182 open after the shaft permits the spring 184 to engage the contact point 183. The connection having been extended to the second or sub-exchange the connector H is now in a position to respond to the impulses for the last two digits of the called number and extend the connection through 105 to the line of substation A' (#2220). When the dial at substation A (#5000) is operated for the third digit (2) the relay 46 is deenergized twice, as for the previous digits. Each time the relay is deenergized for this 110 digit the engagement of springs 109 and 95 furnishes an energizing circuit for the relay 62 of the connector H. This energizing circuit extends from ground G^{20} through 115 springs 95 and 109, springs 100 and 101, side switch wiper 42, shaft wiper 37, side switch wiper 54, shaft wiper 51, trunk conductor 124, relay 62, side switch wiper 148, to the battery lead 80, thence through battery B 120 to ground G. Each time this circuit is closed the relay 62 forces springs 127 and 128 into contact, thereby closing an energizing circuit for the vertical magnet 63. This circuit extends from ground G^{18} 125 through side switch wiper 125, contact point 130

129, springs 127 and 128, vertical magnet 63, contact point 132, side switch wiper 133 to the battery lead 80, thence through battery B to ground G. Since two impulses are sent from substation A, the vertical magnet is energized twice to raise the shaft wipers 64, 65 and 66 two steps to a position opposite the bank level in which are situated the terminals of the desired line #2220. In this case, as before, the relay 48 energizes upon the first impulse and remains in an operated position until all impulses are delivered. When the relay 48 energizes for the third digit it closes an energizing circuit for the relay 68 of the connector H, said circuit extending from ground G¹⁶ through springs 107 and 103, conductor 115, side switch wiper 41, shaft wiper 36, side switch wiper 53, shaft wiper 50, conductor 123, side switch wiper 134, relay 68 to the battery lead 80, thence through battery B to ground G. Relay 68 thereupon energizes to close an energizing circuit from ground G¹⁹ through springs 136 and 135 and through the private magnet 69 to the battery lead 80, thence through battery B to ground G. After the impulses cease the relay 48 deenergizes to open the circuit of relay 68, which in turn deenergizes to open the circuit of the private magnet 69. The deenergization of the private magnet allows the side switch to move into second position. When the side switch reaches second position the wiper 133 places the rotary magnet 67 under the control of the relay 62. When the dial at substation A is operated for the fourth digit (0) the relay 62 responds to the impulses in the same manner as when the third digit (2) was called, but in this case the engagement of springs 127 and 128 closes an energizing circuit for the rotary magnet 67. This circuit extends from ground G¹⁸, side switch wiper 125, contact 130, springs 127 and 128, rotary magnet 67, contact 137 and side switch wiper 133 to battery lead 80. The rotary magnet is energized ten times over this circuit and operates to rotate the switch shaft to carry the wipers onto the terminals of the desired line #2220. In this case, as before, the private magnet 69 is energized upon the first impulse from the substation A, and if the called line is not busy the private magnet deenergizes after the impulses are completed and the side switch is permitted to move into third position, thus completing the connection to the called line. If, however, the called line is busy the private wiper 66 finds the private contact of line #2220 grounded, said ground being supplied by some other occupying connector similar to H, or if the substation #2220 has made a call this ground is supplied by the line switch C'. In either case, when the private wiper rests on this grounded contact an energizing circuit is established extending from said grounded contact through wiper 66, side switch wiper 153 (bearing in mind that the side switch is still in second position), and through the private magnet 69 to battery lead 80, thence through battery B to ground G. The private magnet is maintained energized over this circuit and the side switch locked in second position after the relay 68 is deenergized upon cessation of the impulses. While the side switch is thus locked a circuit is closed for the purpose of giving the calling subscriber the busy-signal. This circuit extends from the battery lead 80 through the secondary winding of the busy-signalling machine J, springs 138 and 139, 141 and 140, side switch wiper 134, in second position, conductor 123, through switches F and E, through substation apparatus and back through switches E and F, through relay 62 to the battery lead 80. The calling subscriber will continue to receive the busy-signal over this circuit until he hangs up his receiver, thus releasing the connection, or until the guarding potential is removed from the private bank contacts, when the side switch will be released to third position and the connection thus completed. If the line #2220 had not been busy when called, the side switch would have been released to third position immediately after the impulses for the last digit (0) were completed. When the side switch wiper 134 reaches third position the trunk conductor 123 is cut through to a spring of relay 62. When the side switch wiper 153 reaches third position it establishes an energizing circuit for the bridge-cut-off relay 192 of the line switch C'. This circuit extends from ground G²⁰ through side switch wiper 153, shaft private wiper 66, and through the relay 192 to the battery lead 80, thence through the battery B to ground G. The relay 192, upon energizing, operates to disconnect ground from the line conductor 156, and the trip magnet of line switch C' from the conductor 157, so as not to interfere with the talking battery circuit of substation A'. The side switch wiper 148, in third position, completes a connection from the battery lead 80 through the springs 149 and 150 and 152 and 151 to the ringer relay 71, whereby the ringer relay is intermittently energized through the medium of the interrupter machine K. The action of this interrupter will be explained later. When the ringer relay 71 energizes it shifts the springs 143 and 146 out of engagement with the springs 144 and 147, respectively, and into engagement with springs 142 and 145. By this action connection is broken between springs 146 and 147, and between 143 and 144, and the ringer generator I is bridged across that portion of the line leading to substation A'. The ringer 193 now receives ringing cur-

rent over a circuit extending from one side of generator I through springs 142 and 143, shaft wiper 64, conductor 157, ringer 193, condenser 194, hook switch springs 195 and 196, conductor 156, ringer relay springs 146 and 145 and back to the other side of the generator I. When the subscriber at substation A' removes the receiver from the hook, the spring 196 is shifted out of engagement with spring 195 and into engagement with spring 197, whereby the transmitter 198 and primary winding of the induction coil 199 are bridged across the line conductors 156 and 157 in place of the ringer 193 and condenser 194. When this is done the substation A' is supplied with talking battery current the first time the ringer relay 71 is deenergized thereafter. It is understood, of course, that the ringer relay 71 is energized intermittently and that the receiver at substation A' might be removed from the hook at a time when the ringer relay is energized and the battery potential is cut off. The circuit for the talking current of substation A' extends from ground G¹⁸ through side switch wiper 125, winding 154 of relay 70, ringer relay springs 147 and 146, shaft wiper 65, line conductor 156, springs 196 and 197, impulse springs 200, primary winding of the induction coil 199, transmitter 198, line conductor 157, shaft wiper 64, ringer relay springs 143 and 144, winding 155 of relay 70 and through side switch wiper 133 to the battery lead 80, thence through the battery B to ground G. The relay 70 energizes upon the closure of this circuit and operates to close contact between springs 158 and 159, 158^a and 159^a and 160 and 149, and to open the contact between springs 149 and 150. The engagement of springs 158 and 159 and 158^a and 159^a extends the conductors 123 and 124 through to the called line. The disengagement of springs 149 and 150 removes the battery connection from the ringer relay 71, so that it cannot be energized again after the called subscriber answers. The engagement of springs 160 and 149 closes an energizing circuit extending from ground G²¹ through relay 72, springs 160 and 149 and side switch wiper 148 to battery lead 80. Upon the closure of this circuit the relay 72 energizes and locks. The locking circuit extends from ground G²¹ through relay 72, springs 161 and 162 and side switch wiper 133 to battery lead 80, thence through battery B to ground G. In its energized position the relay 72 opens the battery connection of the ringer relay 71 at a second point by the separation of springs 151 and 152. The relay 72 will remain locked in its energized position until the switch H is released, opening the circuit of relay 72 at the side switch wiper 133. With this arrangement it will

be seen that after the called subscriber has once answered, his bell will not be rung again after the receiver is hung up even though the calling subscriber does wait some time before restoring his receiver to the switch hook.

I will now explain the action of the interrupter K, by means of which the ringing is made intermittent. The relay 163 is provided with two windings 164 and 165. Winding 164 has a high resistance while the resistance of winding 165 is comparatively low. The ringer relay is so wound that it will operatively energize when included in a circuit in series with the two windings 164 and 165 connected in multiple, but when the relay 71 is connected in series with winding 164 alone said relay 71 will not energize, but relay 163 will attract its armature. Now when the side switch of the connector H first passes to third position the circuit through the hinger relay extends from ground G²² through winding 164 of relay 163, thence through ringer relay 71 and springs 152 and 151 and 150 and 149 and side switch wiper 148 to battery. The relay 163 energizes upon closure of this circuit. When the relay 163 energizes it operates to close contact between springs 168 and 169, whereby an energizing circuit is closed through the motor magnet 170. This circuit extends from ground G²³ through motor magnet 170, interrupter springs 171 and 172 and springs 168 and 169, thence through battery B to ground G. The motor magnet upon energizing attracts its armature 173, which forces the pawl 174 into engagement with the ratchet wheel 175, rotating it one step. When the armature 173 reaches the bottom of its stroke the interrupter springs 171 and 172 are separated, the magnet 170 deenergizes, the armature 173 restores to normal, closing the interrupter springs again, and consequently the magnet 170 is again energized and the ratchet wheel 175 rotated another step. The motor magnet will continue to operate in this manner to give the ratchet wheel 175 a continuous rotary motion as long as the relay 163 remains energized. As the ratchet wheel 175 revolves, the toothed wheel 176 is carried around with it. When the tooth 177 passes from under spring 167 this spring makes contact with spring 166, thus closing the circuit through winding 165. The ringer relay, now receiving current through the windings 164 and 165 in multiple, energizes and bridges the ringer generator I across the line of substation A', as before explained. Each time a tooth of the wheel 176 passes the spring 167 the circuit through the winding 165 is opened and the ringer relay is deenergized. When the receiver at substation A' is removed from the hook and the bat-

ter connection of the ringer relay is broken, as explained, relay 163 deenergizes, opening the circuit of the motor magnet 170.

After a connection has been completed the 5 switches are released by the restoration of the receiver to the switch hook at the calling substation. When the receiver at substation A is hung up the energizing circuit of the relay 46 is broken at a point between the 10 springs 75 and 76. The relay 46 deenergizes and opens the circuit of relay 47 at a point between springs 96 and 97, and also connects the release magnet 49 with the battery B through the springs 96 and 94. As soon as 15 relay 47 deenergizes two circuits are closed, one through the release magnet 49 of the first selector E and one through the release magnet 26 of the line switch C in series with the relay 178. The circuit through the 20 release magnet 49 extends from ground G⁹ through springs 102 and 103, release magnet 49, normal spring 98, contact point 114 and springs 94 and 96 to the battery lead 80, thence through battery B to ground G. The 25 magnet 49 upon energizing restores the selector to normal position, and the circuit of the magnet 49 is opened at a point between spring 98 and contact 114 when the switch shaft reaches its normal position, and the 30 contact will be closed between spring 98 and contact point 99. The other circuit closed by the deenergization of relays 46 and 47 extends from ground G⁹ through springs 102 and 103, relay 178, springs 110 and 111, bank 35 contacts 23 and 22, release magnet 26 to battery lead 80, thence through battery B to ground G. The magnet 26 and relay 178, which are included in this circuit, energize. The relay 26 upon energizing attracts its 40 armature and holds it in readiness to release the switch C. When the relay 178 energizes, the springs 179^a and 180^a are pressed into engagement and a circuit is closed through the relay 47, thereby again energizing this 45 relay. This circuit extends from ground G⁷ through relay 47, contact point 99, spring 98 and springs 180^a and 179^a to battery lead 80, thence through battery B to ground G. When the relay 47 energizes it separates the 50 springs 102 and 103, thereby breaking the circuit through the relay 178 and release magnet 26, as well as its own circuit. Since the relay 47 is slow-acting it maintains the circuit open long enough for the release magnet 26 to deenergize and release the line switch C. The separation of the bank springs 22 and 23 upon the withdrawal of the line switch plunger maintains the circuit of the relay 178 open after the relay 47 55 returns to normal position. When the side switch wiper 43 leaves the third position upon the release of the first selector E, it initiates the release of the second selector F in the following manner: When the side 60 switch wiper 43 leaves its grounded third- 65

position contact the circuit of the release relay 61 of the second selector F is opened. The relay 61 thereupon deenergizes, permitting the spring 118 to engage the spring 119, thereby closing the circuit of the release 70 magnet 60. This circuit extends from ground G¹⁷ through the release magnet 60, springs 118 and 119, contact point 121, normal spring 120 to the battery lead 80, thence through battery B to ground G. The magnet 60 energizes and releases the switch F. When the switch shaft reaches its normal position it forces the spring 120 out of engagement with the contact point 121, thereby opening the energizing circuit of the release magnet 60. The release of the second selector F in turn brings about the release of the connector H by opening the energizing circuit of the release relay 179 at the side switch wiper 55 and shaft wiper 52. The relay 179 upon deenergizing permits the springs 180 and 181 to engage, thereby closing the energizing circuit of the release magnet 182, which energizes to release the connector H. The energizing circuit of the release magnet 182 extends from ground G²⁴ through the magnet 182, springs 180 and 181, contact point 183 and normal spring 184 to the battery lead 80. It is broken when the switch shaft returns to normal position, thereby separating the spring 184 from the contact point 183. The locking circuit of the relay 72 is broken as soon as the side switch wiper 133 leaves the third position upon the release of the connector H. 90

From the foregoing it is evident how a subscriber at substation A in one exchange may obtain connection with a subscriber of a distant exchange. It has been assumed here that the trunks from the second level of the second selector banks lead to connectors H located at a distant exchange, while the trunks from the first level of the second selectors lead to connectors (Fig. 3) located in the same exchange as the selectors E and F (Fig. 1). If the subscriber at substation A had called #2120 (not shown) instead of #2220, the operation of the selectors E and F would have been the same as previously described, except that the second selector wipers would have been raised only one step and have selected a trunk in the first bank level leading to a connector similar to that shown in Fig. 3. When the calling device at the substation A is operated for the second digit the line relay 46 at the first selector E operates in the manner previously described to send two ground impulses to conductor 116. Now, since the second selector wipers are resting on bank contacts of the first level, these ground impulses are transmitted to the connector (Fig. 3) over trunk conductor 124^a and thence through the vertical magnet 185 and side switch wiper 205 to the battery B. The vertical magnet thus 100 105 110 115 120 125 130

receives two impulses and operates in the usual manner to raise the shaft and wipers two steps. The relay 48 of the first selector F energizes as before when the first impulse is sent from the substation and operates to ground the conductor 115. From conductor 115 ground is extended through the second selector F to trunk conductor 123^a, thence through the private magnet 188 to battery B. This circuit through the private magnet 188 remains closed until the last impulse for the digit is received, when the relay 48 de-energizes and cuts ground from conductor 115. The private magnet 188 is thereupon deenergized and allows the side switch to pass to second position. When the side switch passes from first to second position battery is disconnected from the vertical magnet 186 by the wiper 205 and the rotary magnet 187 is connected to battery through the side switch wiper 206. Now, when the calling device is operated for the last digit (0) ten ground impulses are transmitted to the trunk conductor 124^a by the operation 25 of relay 46 at the selector E. Since the rotary magnet 187 of the connector (Fig. 3) is now connected to battery, the said rotary magnet responds to these ten impulses to rotate the shaft wipers onto the tenth contact of the second bank level, which is the terminal of the desired line. The private magnet 188 operates for the last digit as for the third, if the called line is idle, and releases the side switch to third position. If 30 the called line is busy, however, the private wiper finds a grounded contact, as previously explained, and closes a holding circuit through the private magnet 188. The side switch is thus locked in second position 40 and the calling subscriber is given the busy signal. The release of the connector shown in Fig. 3 takes place in the same manner as explained for the connector H.

From the foregoing it will be seen that I provide combined first selectors and repeaters having provisions for feeding battery current for talking purposes to the lines of the calling subscribers. The lines of the called subscribers receive current for talking purposes from the same or a different source, but not through any coils or other devices of the first selectors. The talking current for the called subscribers is fed through the connectors, and does not pass 55 over the trunk or trunks by which calling and called telephone lines are connected together. When the call is from one telephone line to another telephone line in the same exchange a second selector F is used, which 60 selector is without line relays, the actuating magnets thereof being directly controlled by the line relays of the first selector. For a local call of this kind it is also true that the connector, which is shown in Fig. 3, is 65 employed, which connector is also without

line relays, its actuating magnets being controlled by the line relays of the first selector. However, when the call is from a telephone line of one exchange to a telephone line of a subexchange, or of a second exchange, then the connector H, shown in Fig. 2, is employed, which connector has its own individual line relays, such as the relays 68 and 62, the latter being similar to what is ordinarily known as the vertical line relay. 70 The second selector F is, of course, used for both local and long distance calls, such as those just described. Again it will be seen that the line relay or relays of the first selector E serve to repeat calling impulses 75 from two-wire to three-wire line circuits. By this I mean that the original impulses are transmitted over complete metallic line circuits without the necessity of grounding the line at the calling substation; and that these impulses are then repeated by the relay or relays of the first selector in circuits that do not include the two sides of the trunk line in parallel, inasmuch as these circuits necessarily include the ground at each end 80 of the trunk line. In other words, the original impulses transmitted by the calling subscriber are transmitted over circuits including the two sides of the calling telephone line in series, whereas the repeated impulses 85 are transmitted over ground circuits that each include only one side of the trunk line circuit. Thus, as I say, I provide a combined first selector and repeater for extending the connection from a two-wire circuit 90 to a three-wire circuit in the manner explained. 95

What I claim as my invention is:—

1. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including a metallic line circuit for controlling said relay, and instrumentalities independent of said trunk conductors for supplying talking current to the calling and called lines. 115

2. In a common battery telephone system, subscribers' lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit 125

- including a trunk conductor for energizing said magnet, a relay for controlling said circuit, means including a metallic line circuit for controlling said relay, an automatic switch mechanism allotted to and controlled by said relay, and instrumentalities independent of said trunk conductor for supplying talking current to the calling and called lines.
6. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, and instrumentalities independent of said trunk conductors for supplying talking current to the calling and called lines.
7. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including a metallic line circuit for controlling said relay, the said energizing circuits including a ground connection controlled by said relay, and instrumentalities independent of said trunk conductors for supplying talking current to the calling and called lines.
8. In a common battery telephone system, subscribers' lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, and instrumentalities independent of said trunk conductor for supplying talking current to the calling and called lines.
9. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including a metallic line circuit for controlling said relay, the said energizing circuits including a ground connection controlled by said relay, and instrumentalities independent of said trunk conductor for supplying talking current to the calling and called lines.

- 5 talking circuit between two of said lines, said means including a plurality of automatic switches, means for controlling the 5 number of impulses corresponding to the digits of the called number, each switch provided with a propelling mechanism, an actuating magnet for operating said propelling mechanism, circuits including trunk conductors for energizing said magnets, a relay for 10 successively controlling said circuits, means including a metallic line circuit for controlling said relay, an automatic switch mechanism allotted to and controlled by 15 said relay, the said energizing circuits including a ground connection controlled by said relay, and instrumentalities independent of said trunk conductors for supplying talking current to the calling and called 20 lines.
10. In a common battery system, subscribers' lines, means for establishing a talking circuit between two of said lines, said means including trunks divided into groups, a plurality of automatic trunk-selecting switches, each switch provided with a propelling mechanism, an actuating magnet for operating said propelling mechanism, circuits including trunk conductors for energizing 25 said magnets, a relay for successively controlling said circuits, means including a metallic line circuit for controlling said relay, an automatic switch mechanism normally connected to and controlled by said relay, 30 said automatic switch mechanism having motion first in one plane to select a group and then motion in a plane at right-angles to said other plane to automatically select an idle trunk in the predetermined group, the said energizing circuits including a 35 ground connection controlled by said relay, and instrumentalities independent of said trunk conductors for supplying talking current to the calling and called lines.
- 40 11. In a common battery telephone system, subscribers' lines, means for establishing a talking circuit between two of said lines, said means including an automatic step-by-step switch, means for controlling the operation of said switch by a varying number 45 of impulses corresponding to the digits of the called number, a magnet having its armature provided with means for directly actuating or propelling said switch, a circuit including a trunk conductor for energizing 50 said magnet, a relay for controlling said circuit, means including a metallic line circuit for controlling said relay, means for automatically extending connection to said 55 automatic switch, the said energizing circuit including a ground connection controlled by said relay, and instrumentalities independent of said trunk conductor for 60 supplying talking current to the calling and called lines.
- 65 12. In a common battery telephone system, subscribers' lines, means for establishing a talking circuit between two of said lines, said means including a plurality of automatic switches, means for controlling 70 the operation of said switches by a varying number of impulses corresponding to the digits of the called number, each switch provided with a propelling mechanism, an actuating magnet for operating said propelling 75 mechanism, circuits including trunk conductors for energizing said magnets, a relay for successively controlling said circuits, means including a metallic line circuit for controlling said relay, means for automatically extending connection to said 80 automatic switches, the said energizing circuits including a ground connection controlled by said relay, and instrumentalities independent of said trunk conductors for supplying talking current to the calling and called lines.
- 85 13. In a common battery telephone system, subscribers' lines, means for establishing a talking circuit between two of said lines, said means including an automatic step-by-step switch, a magnet having its armature provided with means for directly actuating or propelling said switch, a circuit including a trunk conductor for energizing 90 said magnet, a relay for controlling said circuit, means including a metallic line circuit for controlling said relay, a pair of voice-current trunk conductors between which said relay is permanently bridged, and instrumentalities independent of said first-mentioned trunk conductor for supplying talking current to the calling and called lines.
- 95 14. In a common battery telephone system, subscribers' lines, means for establishing a talking circuit between two of said lines, said means including a plurality of automatic switches, each switch provided with a propelling mechanism, an actuating magnet for operating said propelling mechanism, circuits including trunk conductors for energizing said circuits, a relay for successively controlling said circuits, means including a metallic line circuit for controlling 100 said relay, a pair of voice-current trunk conductors between which said relay is permanently bridged, and instrumentalities independent of said first-mentioned trunk conductors for supplying talking current to the calling and called lines.
- 105 15. In a common battery telephone system, subscribers' lines, means for establishing a talking circuit between two of said lines, said means including an automatic step-by-step switch, a magnet having its armature provided with means for directly actuating or propelling said switch, a circuit including a trunk conductor for energizing 110 said magnet, a relay for controlling said circuit, means including a metallic line circuit for controlling said relay, a pair of voice-current trunk conductors between which said relay is permanently bridged, and instrumentalities independent of said first-mentioned trunk conductors for supplying talking current to the calling and called lines.
- 115 16. In a common battery telephone system, subscribers' lines, means for establishing a talking circuit between two of said lines, said means including an automatic step-by-step switch, a magnet having its armature provided with means for directly actuating or propelling said switch, a circuit including a trunk conductor for energizing 120 said magnet, a relay for controlling said circuit, means including a metallic line circuit for controlling said relay, a pair of voice-current trunk conductors between which said relay is permanently bridged, and instrumentalities independent of said first-mentioned trunk conductors for supplying talking current to the calling and called lines.
- 125 17. In a common battery telephone system, subscribers' lines, means for establishing a talking circuit between two of said lines, said means including an automatic step-by-step switch, a magnet having its armature provided with means for directly actuating or propelling said switch, a circuit including a trunk conductor for energizing 130 said magnet, a relay for controlling said circuit, means including a metallic line circuit for controlling said relay, a pair of voice-current trunk conductors between which said relay is permanently bridged, and instrumentalities independent of said first-mentioned trunk conductors for supplying talking current to the calling and called lines.

- circuit for controlling said relay, an automatic switch mechanism allotted to and controlled by said relay, a pair of voice-current trunk conductors between which said relay 5 is permanently bridged, and instrumentalities independent of said first-mentioned trunk conductor for supplying talking current to the calling and called lines.
16. In a common battery telephone system, subscribers' lines, means for establishing a talking circuit between two of said lines, said means including a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling 15 said relay, an automatic switch mechanism allotted to and controlled by said relay, a pair of voice-current trunk conductors between which said relay is permanently bridged, and instrumentalities independent 20 of said first-mentioned trunk conductors for supplying talking current to the calling and called lines.
17. In a common battery system, subscribers' lines, means for establishing a talking circuit between two of said lines, said means including trunks divided into groups, an automatic step-by-step switch, a magnet having its armature provided with means for directly actuating or propelling said 25 switch, a circuit including a trunk conductor for energizing said magnet, a relay for controlling said circuit, means including a metallic line circuit for controlling said relay, an automatic switch mechanism allotted 30 to and controlled by said relay, said automatic switch mechanism having motion first in one plane to select a group and then motion in a plane at right-angles to said other plane to automatically select an idle trunk 35 in the predetermined group, a pair of voice-current trunk conductors between which said relay is permanently bridged, and instrumentalities independent 40 of said first-mentioned trunk conductor for supplying talking current to the calling and called lines.
18. In a common battery system, subscribers' lines, means for establishing a talking circuit between two of said lines, said means including trunks divided into groups, a plurality of automatic switches, each switch provided with a propelling mechanism, an actuating magnet for operating 45 said propelling mechanism, circuits including trunk conductors for energizing said magnets, a relay for successively controlling said circuits, means including a metallic line circuit for controlling said relay, an automatic switch mechanism allotted to and 50 controlled by said relay, said automatic
- switch mechanism having motion first in one plane to select a group and then motion in a plane at right-angles to said other plane to automatically select an idle trunk in the predetermined group, a pair of voice-current trunk conductors between which said relay is permanently bridged, and instrumentalities independent of said first-mentioned trunk conductors for supplying talking current to the calling and called lines. 70
19. In a common battery telephone system, subscribers' lines, means for establishing a talking circuit between two of said lines, said means including an automatic step-by-step switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, a pair of voice-current trunk conductors between which said relay is permanently bridged, and instrumentalities independent of said first-mentioned trunk conductor for supplying talking current to the calling and called lines. 75
20. In a common battery telephone system, subscribers' lines, means for establishing a talking circuit between two of said lines, said means including a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, a pair of voice-current trunk conductors between which said relay is permanently bridged, and instrumentalities independent of said first-mentioned trunk conductors for supplying talking current to the calling and called lines. 80
21. In a telephone system, subscribers' lines, means for establishing a talking circuit between two of said lines, said means including a first selector common to a plurality of said lines provided with a line relay normally connected thereto, means for controlling the operation of said switch by a varying number of impulses corresponding to the digits of the called number, said impulses delivered over a circuit including the two sides of a calling line in series, a trunk line adapted to be seized by said first selector, an automatic switch having a progressively movable element, a magnet having an armature for driving said element, a circuit for said magnet extending over said trunk line and controlled by said relay after the first selector has seized 85

- said trunk, and means independent of said selector for supplying talking current to any substation called through the medium thereof.
- 5 22. In a telephone system, subscribers' lines, means for establishing a talking circuit between two of said lines, said means including an automatic switch common to a plurality of said lines and provided with a
- 10 line relay, means for controlling the operation of said switch by a varying number of impulses corresponding to the digits of the called number, a trunk line adapted to be seized by said switch, a circuit for controlling said relay including the two sides of a calling line in series, a switch having a progressively movable element, a magnet having an armature for driving said element, a circuit for said magnet extending over said trunk line and controlled by said relay, and means independent of said automatic switch for supplying talking current to any substation called through the medium thereof.
- 15 23. In a telephone station, subscribers' lines, means for establishing a talking circuit between two of said lines, said means including a first selector common to a plurality of said lines and provided with a line relay normally connected thereto, a circuit including the two sides of said talking circuit in series for controlling said relay, means for controlling the operation of said switch by a varying number of impulses corresponding to the digits of the called number, a trunk line adapted to be seized by said first selector, an automatic switch having wipers, a magnet having an armature for driving said wipers, a circuit for said magnet extending over said trunk line and controlled by said line relay after the first selector has seized said trunk line, suitable means for extending a connection to said first selector, and means independent of said first selector for supplying current to any substation called through the medium thereof.
- 20 24. In a telephone system, subscribers' lines, means for establishing a talking circuit between two of said lines, said means including an automatic switch common to a plurality of said lines and provided with a
- 25 26. In a telephone exchange trunking system, a talking circuit, an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, a connector having a line relay controlled by said relay, and an actuating magnet controlled by said line relay.
- 30 27. In a telephone exchange trunking system, a talking circuit, a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including the two sides of said talking circuit in series for controlling said relay, a connector having a line relay controlled by said relay, and an actuating magnet controlled by said line relay.
- 35 28. In a telephone exchange trunking system, the combination of a talking circuit, an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 40 29. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 45 30. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 50 31. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 55 32. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 60 33. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.
- 65 34. In a telephone exchange trunking system, the combination of a talking circuit, a plurality of automatic switches, means for controlling the operation of said switches by a varying number of impulses corresponding to the digits of the called number, a magnet having its armature provided with means for directly actuating or propelling said switch, a circuit including a trunk conductor for energizing said magnet, a relay for controlling said circuit, means including the two sides of said talking circuit in series for controlling said relay, an automatic switch mechanism allotted to and controlled by said relay, a connector having a line relay controlled by said relay, and an actuating magnet controlled by said line relay.

- nism allotted to and controlled by said relay, a connector having a line relay controlled by said relay, and an actuating magnet controlled by said line relay.
- 5 29. In a telephone exchange trunking system having trunks divided into groups, the combination of a talking circuit, an automatic step-by-step trunk-selecting switch, a magnet having its armature provided with 70 means for directly actuating or propelling said switch, a circuit including a trunk conductor for energizing said magnet, a relay for controlling said circuit, means including the two sides of said talking circuit in series 75 for controlling said relay, an automatic switch mechanism normally connected to and controlled by said relay, said automatic switch mechanism having motion first in one plane to select a group and then motion in a 80 plane at right-angles to said other plane to automatically select an idle trunk in the predetermined group, a connector having a line relay controlled by said relay, and an actuating magnet controlled by said line relay.
- 15 25 30. In a telephone exchange trunking system having trunks divided into groups, the combination of a talking circuit, a plurality of automatic trunk-selecting switches, each switch provided with a propelling mechanism, an actuating magnet for operating 85 said propelling mechanism, circuits including trunk conductors for energizing said magnets, a relay for successively controlling said circuits, means including the two sides 90 of said talking circuit in series for controlling said relay, an automatic switch mechanism normally connected to and controlled by said relay, said automatic switch mechanism having motion first in one plane to 95 select a group and then motion in a plane at right-angles to said other plane to automatically select an idle trunk in the predetermined group, a connector having a line relay controlled by said relay, and an actuating magnet controlled by said line relay.

- tem, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, means at the central station for supplying talking current over said metallic circuit, a connector having a line relay controlled by said relay, an actuating magnet controlled by said line relay, and means in the connector for feeding talking current to any substation called through the medium thereof.
37. In a telephone exchange trunking system having trunks divided into groups, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, means at the central station for supplying talking current over said metallic circuit, a connector having a line relay controlled by said relay, an actuating magnet controlled by said line relay, and means in the connector for feeding talking current to any substation called through the medium thereof.
38. In a telephone exchange trunking system having trunks divided into groups, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, means at the central station for supplying talking current over said metallic circuit, a connector having a line relay controlled by said relay, an actuating magnet controlled by said line relay, and means in the connector for feeding talking current to any substation called through the medium thereof.
39. In a telephone exchange trunking system, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, means at the central station for supplying talking current over said metallic circuit, a connector having a line relay controlled by said relay, an actuating magnet controlled by said line relay, and means in the connector for feeding talking current to any substation called through the medium thereof.
40. In a telephone exchange trunking system, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, means at the central station for supplying talking current over said metallic circuit, a connector having a line relay controlled by said relay, an actuating magnet controlled by said line relay, and means in the connector for feeding talking current to any substation called through the medium thereof.
41. In a telephone exchange trunking system, an automatic step-by-step trunk-selecting switch, a magnet having its armature provided with means for directly actuating or propelling said switch, a circuit including a trunk conductor for energizing said magnet, a relay for controlling said circuit, means including a metallic line circuit for controlling said relay, and a connector provided with a line relay permanently connected with the line circuit thereof, the said energizing circuit including a ground connection controlled by said first-mentioned relay.
42. In a telephone exchange trunking system, a plurality of automatic trunk-selecting switches, each switch provided with a propelling mechanism, an actuating magnet for operating said propelling mechanism, circuits including trunk conductors for energizing said magnets, a relay for successively controlling said circuits, means including a metallic line circuit for controlling said relay, and a connector provided with a line relay permanently connected with the line circuit thereof, the said energizing circuits

including a ground connection controlled by said first-mentioned relay.

43. In a telephone exchange trunking system, the combination of an automatic step-by-step trunk-selecting switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, and a connector provided with a line relay permanently connected with the line circuit thereof, the said energizing circuit including a ground connection controlled by said relay.
- 10 44. In a telephone exchange trunking system, the combination of a plurality of automatic trunk-selecting switches, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, and a connector provided with a line relay permanently connected with the line circuit thereof, the said energizing circuit including a ground connection controlled by said first-mentioned relay.
- 20 45. In a telephone exchange trunking system having trunks divided into groups, the combination of an automatic step-by-step trunk-selecting switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a connector provided with a line relay permanently connected with the line circuit thereof, the said energizing circuit including a ground connection controlled by said first-mentioned relay.
- 30 46. In a telephone exchange trunking system having trunks divided into groups, the combination of a plurality of automatic trunk-selecting switches, each switch provided with a propelling mechanism, an actuating magnet for operating said propelling mechanism, circuits including trunk conductors for energizing said magnets, a relay for successively controlling said circuits, means including a metallic line circuit for controlling said relay, and a connector provided with a line relay responsive to said relay, which line relay controls the vertical and rotary motion of said connector.
- 40 47. In a telephone exchange trunking system, the combination of an automatic step-by-step trunk-selecting switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, and a connector provided with a line relay permanently connected with the line circuit thereof, the said energizing circuit including a ground connection controlled by said first-mentioned relay.
- 50 48. In a telephone exchange trunking system, the combination of a plurality of automatic trunk-selecting switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, and a connector provided with a line relay permanently connected with the line circuit thereof, the said energizing circuit including a ground connection controlled by said first-mentioned relay.
- 60 49. In a telephone exchange trunking system, an automatic step-by-step switch, a magnet having its armature provided with means for directly actuating or propelling said switch, a circuit including a trunk conductor for energizing said magnet, a relay for controlling said circuit, means including a metallic line circuit for controlling said relay, a pair of voice-current trunk conductors between which said relay is permanently bridged, and a vertical and rotary motion connector provided with a line relay responsive to said relay, which line relay controls the vertical and rotary motion of said connector.
- 55 50. In a telephone exchange trunking system, a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, and a connector provided with a line relay responsive to said relay, which line relay controls the vertical and rotary motion of said connector.

cuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a connector provided with a line relay permanently connected with the line circuit thereof, the said energizing circuits including a ground connection controlled by said first-mentioned relay.

43. In a telephone exchange trunking system, the combination of an automatic step-by-step trunk-selecting switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, and a connector provided with a line relay permanently connected with the line circuit thereof, the said energizing circuit including a ground connection controlled by said first-mentioned relay.

44. In a telephone exchange trunking system, the combination of a plurality of automatic trunk-selecting switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, and a connector provided with a line relay permanently connected with the line circuit thereof, the said energizing circuit including a ground connection controlled by said first-mentioned relay.

100 105 110 115 120 125

45. In a telephone exchange trunking system, an automatic step-by-step switch, a magnet having its armature provided with means for directly actuating or propelling said switch, a circuit including a trunk conductor for energizing said magnet, a relay for controlling said circuit, means including a metallic line circuit for controlling said relay, a pair of voice-current trunk conductors between which said relay is permanently bridged, and a vertical and rotary motion connector provided with a line relay responsive to said relay, which line relay controls the vertical and rotary motion of said connector.

46. In a telephone exchange trunking system, a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, and a connector provided with a line relay responsive to said relay, which line relay controls the vertical and rotary motion of said connector.

ing trunk conductors for energizing said magnets, a relay for successively controlling said circuits, means including a metallic line circuit for controlling said relay, a pair of voice-current trunk conductors between which said relay is permanently bridged, and a vertical and rotary motion connector provided with a line relay responsive to said relay, which line relay controls the vertical and rotary motion of said connector.

51. In a telephone exchange trunking system, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, a pair of voice-current trunk conductors between which said relay is permanently bridged, and a vertical and rotary motion connector provided with a line relay responsive to said relay, which line relay controls the vertical and rotary motion of said connector.

52. In a telephone exchange trunking system, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, a pair of voice-current trunk conductors between which said relay is permanently bridged, and a vertical and rotary motion connector provided with a line relay responsive to said relay, which line relay controls the vertical and rotary motion of said connector.

53. In a telephone exchange trunking system having trunks divided into groups, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, a pair of voice-current trunk conductors between which said relay is permanently bridged, and a vertical and rotary motion connector provided with a line relay re-

sponsive to said relay, which line relay controls the vertical and rotary motion of said connector.

54. In a telephone exchange trunking system having trunks divided into groups, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, a pair of voice-current trunk conductors between which said relay is permanently bridged, and a vertical and rotary motion connector provided with a line relay responsive to said relay, which line relay controls the vertical and rotary motion of said connector.

55. In a telephone exchange trunking system, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, a pair of voice-current trunk conductors between which said relay is permanently bridged, and a vertical and rotary motion connector provided with a line relay responsive to said relay, which line relay controls the vertical and rotary motion of said connector.

56. In a telephone exchange trunking system, the combination of a plurality of automatic switches, each switch provided with a propelling mechanism, an actuating magnet for operating said propelling mechanism, circuits including trunk conductors for energizing said magnets, a relay for successively controlling said circuits, means including a metallic line circuit for controlling said relay, means for automatically extending connection to said automatic switches, a pair of voice-current trunk conductors between which said relay is permanently bridged, and a vertical and rotary motion connector provided with a line relay responsive to said relay, which line relay controls the vertical and rotary motion of said connector.

57. In a telephone exchange repeater system, subscribers' lines, a plurality of trunks, a plurality of automatic switches, means for controlling the operation of said switches

by a varying number of impulses corresponding to the digits of the called number, each switch provided with a propelling mechanism, an actuating magnet for operating said propelling mechanism, ground circuits including only one side of said trunks for energizing said magnets, a relay for successively controlling said circuits, and means including the two sides of a calling line in series for controlling said relay.

58. In a telephone exchange repeater system, subscribers' lines, the combination of a plurality of trunks, a plurality of automatic switches, means for controlling the operation of said switches by a varying number of impulses corresponding to the digits of the called number, each switch provided with a propelling mechanism, an actuating magnet for operating said propelling mechanism, ground circuits including only one side of said trunks for energizing said magnets, a relay for successively controlling said circuits, means including the two sides of the calling line in series for controlling said relay, and an automatic switch mechanism allotted to and controlled by said relay.

59. In a telephone exchange repeater system having trunks divided into groups, subscribers' lines, the combination of a plurality of automatic trunk-selecting switches, each switch provided with a propelling mechanism, an actuating magnet for operating said propelling mechanism, ground circuits including only one side of said trunks for energizing said magnets, a relay for successively controlling said circuits, means including the two sides of a calling line in series for controlling said relay, and an automatic switch mechanism normally connected to and controlled by said relay, said automatic switch mechanism having motion first in one plane to select a group and then motion in a plane at right-angles to said other plane to automatically select an idle trunk in the predetermined group.

60. In a telephone exchange repeater system, subscribers' lines, the combination of a plurality of trunks, a plurality of automatic switches, means for controlling the operation of said switches by a varying number of impulses corresponding to the digits of the called number, each switch provided with a propelling mechanism, an actuating magnet for operating said propelling mechanism, ground circuits including only one side of said trunks for energizing said magnets, a relay for successively controlling said circuits, means including the two sides of a calling line in series for controlling said relay, and means for automatically extending connection to said automatic switches.

61. In a telephone exchange repeater system, a trunk, an automatic step-by-step switch, means for controlling the operation of said switch by a varying number of im-

pulses corresponding to the digits of the called number, a magnet having its armature provided with means for directly actuating or propelling said switch, a ground circuit including only one side of said trunk for energizing said magnet, a relay for controlling said circuit, means including a metallic line circuit for controlling said relay, and means at the central station for supplying talking current over said metallic circuit.

62. In a telephone exchange repeater system, the combination of a trunk, an automatic step-by-step switch, means for controlling the operation of said switch by a varying number of impulses corresponding to the digits of the called number, a magnet having its armature provided with means for directly actuating or propelling said switch, a ground circuit including only one side of said trunk for energizing said magnet, a relay for controlling said circuit, means including a metallic line circuit for controlling said relay, an automatic switch mechanism allotted to and controlled by said relay, and means at the central station for supplying talking current over said metallic circuit.

63. In a telephone exchange repeater system, the combination of a plurality of trunks, a plurality of automatic switches, means for controlling the operation of said switches by a varying number of impulses corresponding to the digits of the called number, each switch provided with a propelling mechanism, an actuating magnet for operating said propelling mechanism, ground circuits including only one side of said trunks for energizing said magnets, a relay for successively controlling said circuits, means including a metallic line circuit for controlling said relay, an automatic switch mechanism allotted to and controlled by said relay, and means at the central station for supplying talking current over said metallic circuit.

64. In a telephone exchange repeater system having trunks divided into groups, the combination of a plurality of automatic trunk-selecting switches, each switch provided with a propelling mechanism, an actuating magnet for operating said propelling mechanism, ground circuits including only one side of said trunks for energizing said magnets, a relay for successively controlling said circuits, means including a metallic line circuit for controlling said relay, an automatic switch mechanism normally connected to and controlled by said relay, said automatic switch mechanism having motion first in one plane to select a group and then motion in a plane at right-angles to said other plane to automatically select an idle trunk in the predetermined group, and means at the central station for supplying talking current over said metallic circuit.

65. In a telephone exchange repeater system, the combination of a trunk, an automatic step-by-step switch, means for controlling the operation of said switch by a varying number of impulses corresponding to the digits of the called number, a magnet having its armature provided with means for directly actuating or propelling said switch, a ground circuit including only one side of said trunk for energizing said magnet, a relay for controlling said circuit, means including a metallic line circuit for controlling said relay, means for automatically extending connection to said automatic switch, and means at the central station for supplying talking current over said metallic circuit.
66. In a telephone exchange repeater system, the combination of a plurality of trunks, a plurality of automatic switches, means for controlling the operation of said switches by a varying number of impulses corresponding to the digits of the called number, each switch provided with a propelling mechanism, an actuating magnet for operating said propelling mechanism, ground circuits including only one side of said trunks for energizing said magnet, a relay for successively controlling said circuits, means including a metallic line circuit for controlling said relay, means for automatically extending connection to said automatic switches, and means at the central station for supplying talking current over said metallic circuit.
67. In a telephone exchange repeater system, a trunk, an automatic step-by-step switch, a magnet having its armature provided with means for directly actuating or propelling said switch, a ground circuit including only one side of said trunk for energizing said magnet, a relay for controlling said circuit, means including a metallic line circuit for controlling said relay, and a pair of voice-current trunk conductors between which said relay is permanently bridged.
68. In a telephone exchange repeater system, a plurality of trunks, a plurality of automatic switches, each switch provided with a propelling mechanism, and actuating magnet for operating said propelling mechanism, ground circuits including only one side of said trunks for energizing said magnets, a relay for successively controlling said circuits, means including a metallic line circuit for controlling said relay, and a pair of voice-current trunk conductors between which said relay is permanently bridged.
69. In a telephone exchange repeater system, the combination of a trunk, an automatic step-by-step switch, a magnet having its armature provided with means for directly actuating or propelling said switch, a ground circuit including only one side of said trunk for energizing said magnet, a relay for controlling said circuit, means including a metallic line circuit for controlling said relay, an automatic switch mechanism allotted to and controlled by said relay, and a pair of voice-current trunk conductors between which said relay is permanently bridged.
70. In a telephone exchange repeater system, the combination of a plurality of trunks, a plurality of automatic switches, each switch provided with a propelling mechanism, an actuating magnet for operating said propelling mechanism, ground circuits including only one side of said trunks for energizing said magnets, a relay for successively controlling said circuits, means including a metallic line circuit for controlling said relay, an automatic switch mechanism allotted to and controlled by said relay, and a pair of voice-current trunk conductors between which said relay is permanently bridged.
71. In a telephone exchange repeater system having trunks divided into groups, the combination of an automatic step-by-step switch, a magnet having its armature provided with means for directly actuating or propelling said switch, a ground circuit including only one side of a trunk for energizing said magnet, a relay for controlling said circuit, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a pair of voice-current trunk conductors between which said relay is permanently bridged.
72. In a telephone exchange repeater system having trunks divided into groups, the combination of a plurality of automatic switches, each switch provided with a propelling mechanism, an actuating magnet for operating said propelling mechanism, ground circuits including only one side of said trunks for energizing said magnets, a relay for successively controlling said circuits, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a pair of voice-current trunk conductors between which said relay is permanently bridged.
73. In a telephone exchange repeater system, the combination of a trunk, an automatic step-by-step switch, a magnet having its armature provided with means for directly actuating or propelling said switch, a ground circuit including only one side of said trunk for energizing said magnet, a relay for controlling said circuit, means including a metallic line circuit for controlling said relay, an automatic switch mechanism allotted to and controlled by said relay, and a pair of voice-current trunk conductors between which said relay is permanently bridged.

rectly actuating or propelling said switch, a ground circuit including only one side of said trunk for energizing said magnet, a relay for controlling said circuit, means including a metallic line circuit for controlling said relay, means for automatically extending connection to said automatic switch, and a pair of voice-current trunk conductors between which said relay is permanently bridged.

74. In a telephone exchange repeater system, the combination of a plurality of trunks, a plurality of automatic switches, each switch provided with a propelling mechanism, an actuating magnet for operating said propelling mechanism, ground circuits including only one side of said trunks for energizing said magnets, a relay for successively controlling said circuits, means including a metallic line circuit for controlling said relay, means for automatically extending connection to said automatic switches, and a pair of voice-current trunk conductors between which said relay is permanently bridged.

75. In a common battery telephone system, subscribers' lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including two sides of the talking circuit in series for controlling said relay, and instrumentalities independent of said trunk conductor for supplying talking current to the calling and called lines.

76. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including two sides of the talking circuit in series for controlling said relay, and instrumentalities independent of said trunk conductors for supplying talking current to the calling and called lines.

77. In a common battery telephone system, subscribers' lines, means for establishing a talking circuit between two of said lines, said means including an automatic

step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including two sides of the talking circuit in series for controlling said relay, an automatic switch mechanism allotted to and controlled by said relay, and instrumentalities independent of said trunk conductor for supplying talking current to the calling and called lines.

78. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including two sides of the talking circuit in series for controlling said relay, an automatic switch mechanism allotted to and controlled by said relay, and instrumentalities independent of said trunk conductors for supplying talking current to the calling and called lines.

79. In a common battery system, subscribers' lines, means for establishing a talking circuit between two of said lines, said means including trunks divided into groups, an automatic step-by-step trunk-selecting switch, a magnet having its armature provided with means for directly actuating or propelling said switch, a circuit including a trunk conductor for energizing said magnet, a relay for controlling said circuit, means including two sides of the talking circuit in series for controlling said relay, an automatic switch mechanism normally connected to and controlled by said relay, said automatic switch mechanism having motion first in one plane to select a group and then motion in a plane at right-angles to said other plane to automatically select an idle trunk in the predetermined group, and instrumentalities independent of said trunk conductor for supplying talking current to the calling and called lines.

80. In a common battery system, subscribers' lines, means for establishing a talking circuit between two of said lines, said means including trunks divided into groups, a plurality of automatic trunk-selecting switches, each switch provided with a propelling mechanism, an actuating magnet for operating said propelling mechanism, circuits

- including trunk conductors for energizing said magnets, a relay for successively controlling said circuits, means including two sides of the talking circuit in series for controlling said relay, an automatic switch mechanism normally connected to said relay, said automatic switch mechanism having motion first in one plane to select a group and then motion in a plane at right-angles to said other plane to automatically select an idle trunk in the predetermined group, and instrumentalities independent of said trunk conductors for supplying talking current to the calling and called lines.
81. In a common battery telephone system, subscriber's lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including two sides of the talking circuit in series for controlling said relay, means for automatically extending connection to said automatic switch, and instrumentalities independent of said trunk conductor for supplying talking current to the calling and called lines.
82. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including two sides of the talking circuit in series for controlling said relay, means for automatically extending connection to said automatic switches, and instrumentalities independent of said trunk conductors for supplying talking current to the calling and called lines.
83. In a common battery telephone system, subscribers' lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including two sides of the talking circuit in series for controlling said relay, the said energizing circuit including a ground connection controlled by said relay, and instrumentalities independent of said trunk conductor for supplying talking current to the calling and called lines.
84. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for progressively controlling said circuits, means including two sides of the talking circuit in series for controlling said relay, the said energizing circuits including a ground connection controlled by said relay, and instrumentalities independent of said trunk conductors for supplying talking current to the calling and called lines.
85. In a common battery telephone system, subscribers' lines, means for establishing a talking circuit between two of said lines, said means including an automatic step-by-step switch, means for controlling the operation of said switch by a varying number of impulses corresponding to the digits of the called number, a magnet having its armature provided with means for directly actuating or propelling said switch, a circuit including a trunk conductor for energizing said magnet, a relay for controlling said circuit, means including two sides of the talking circuit in series for controlling said relay, an automatic switch mechanism allotted to and controlled by said relay, the said energizing circuit including a ground connection controlled by said relay, and instrumentalities independent of said trunk conductor for supplying talking current to the calling and called lines.
86. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including two sides of the talking circuit in series for controlling said relay, an automatic switch mechanism allotted to and controlled by said relay, the said energizing circuit including a ground connection controlled by said relay, and instrumentalities independent of said trunk conductor for supplying talking current to the calling and called lines.

cuits including a ground connection controlled by said relay, and instrumentalities independent of said trunk conductors for supplying talking current to the calling and 5 called lines.

87. In a common battery system, subscribers' lines, means for establishing a talking circuit between two of said lines, said means including trunks divided into groups, 10 an automatic step-by-step trunk-selecting switch, a magnet having its armature provided with means for directly actuating or propelling said switch, a circuit including a trunk conductor for energizing said magnet, 15 a relay for controlling said circuit, means including two sides of the talking circuit in series for controlling said relay, an automatic switch mechanism normally connected to and controlled by said relay, said automatic 20 switch mechanism having motion first in one plane to select a group and then motion in a plane at right-angles to said other plane to automatically select an idle trunk in the predetermined group, the said energizing circuit including a ground connection controlled by said relay, and instrumentalities independent of said trunk conductor for 25 supplying talking current to the calling and called lines.

88. In a common battery system, subscribers' lines, means for establishing a talking circuit between two of said lines, said means including trunks divided into groups, a plurality of automatic trunk-selecting 30 switches, each switch provided with a propeller for operating said propelling mechanism, a propelling mechanism, an actuating magnet for operating said propelling mechanism, circuits including trunk conductors for energizing 35 said magnets, a relay for successively controlling said circuits, means including two sides of the talking circuit in series for controlling said relay, an automatic switch mechanism normally connected to and 40 controlled by said relay, said automatic switch mechanism having motion first in one plane to select a group and then motion in a plane at right-angles to said other plane to automatically select an idle trunk 45 in the predetermined group, the said energizing circuits including a ground connection controlled by said relay, and instrumentalities independent of said trunk conductors for 50 supplying talking current to the calling and called lines.

89. In a common battery telephone system, subscribers' lines, means for establishing a talking circuit between two of said lines, said means including an automatic 55 step-by-step switch, means for controlling the operation of said switch by a varying number of impulses corresponding to the digits of the called number, a magnet having its armature provided with means for directly actuating or propelling said switch,

a circuit including a trunk conductor for energizing said magnet, a relay for controlling said circuit, means including two sides of the talking circuit in series for controlling said relay, means for automatically extending connection to said automatic switch, the said energizing circuit including a ground connection controlled by said relay, and instrumentalities independent of said trunk conductor for supplying talking current to the calling and called lines.

90. In a common battery telephone system, subscribers' lines, means for establishing a talking circuit between two of said lines, said means including a plurality of automatic switches, means for controlling the operation of said switches by a varying number of impulses corresponding to the digits of the called number, each switch provided with a propelling mechanism, an actuating magnet for operating said propelling mechanism, circuits including trunk conductors for energizing said magnets, a relay for successively controlling said circuits, means including two sides of the talking circuit in series for controlling said relay, means for automatically extending connection to said automatic switches, the said energizing circuits including a ground connection controlled by said relay, and instrumentalities independent of said trunk conductors for supplying talking current to the calling and called lines.

91. In a telephone system, subscribers' lines, means for establishing a talking circuit between two of said lines, said means including a first selector common to a plurality of said lines and provided with a line relay normally connected thereto, means for controlling the operation of said switch by a varying number of impulses corresponding to the digits of the called number, a trunk line adapted to be seized by said first selector, an automatic switch having wipers, a magnet having an armature for driving said wipers, a circuit for said magnet extending over said trunk line and controlled by said relay after the first selector has seized the said trunk line, said relay controlled over two sides of the talking circuit in series, and means independent of said first selector for supplying talking current to any substation called through the medium thereof.

92. In a telephone system, subscribers' lines, means for establishing a talking circuit between two of said lines, said means including an automatic switch common to a plurality of said lines provided with a line relay, means for controlling the operation of said switch by a varying number of impulses corresponding to the digits of the called number, a trunk line adapted to be seized by said switch, a switch having wipers, a magnet having an armature for

driving said wipers, a circuit for said magnet extending over said trunk line and controlled by said relay, said relay controlled over two sides of the talking circuit in 5 series, and means independent of said automatic switch for supplying talking current to any substation called through the medium thereof.

93. In a telephone system, subscribers' 10 lines, means for establishing a talking circuit between two of said lines, said means including a first selector common to a plurality of said lines and provided with a line relay normally connected thereto, means for 15 controlling the operation of said switch by a varying number of impulses corresponding to the digits of the called number, a trunk line adapted to be seized by said first selector, an automatic switch having wipers, 20 a magnet having an armature for driving said wipers, a circuit for said magnet extending over said trunk line and controlled by said relay after the first selector has seized the said trunk line, said relay controlled over two sides of the talking circuit 25 in series, suitable means for extending connection to said first selector, and means independent of said first selector for supplying talking current to any substation called 30 through the medium thereof.

94. In a telephone system, subscribers' 35 lines, means for establishing a talking circuit between two of said lines, said means including an automatic switch common to a plurality of lines and provided with a line relay, means for controlling the operation of said switch by a varying number of impulses corresponding to the digits of the called number, a trunk line adapted to be 40 seized by said switch, a switch having wipers, a magnet having an armature for driving said wipers, a circuit for said magnet extending over said trunk line and controlled by said relay, said relay controlled 45 over two sides of the talking circuit in series, a selector also controllable by said relay, and means independent of said automatic switch for supplying talking current to any substation called through the medium thereof, said selector being operative 50 for switching in accordance with a digit of the called number.

95. In a telephone exchange repeater system having trunks divided into groups, the 55 combination of a plurality of automatic trunk-selecting switches, each switch provided with a propelling mechanism, an actuating magnet for operating said propelling mechanism, ground circuits including only one side of said trunks for energizing said magnets, a relay for successively controlling said circuits, means including two sides of the talking circuit in series for controlling said relay, and an automatic 60 switch mechanism normally connected to and

controlled by said relay, said automatic switch mechanism having motion first in one plane to select a group and then motion in a plane at right-angles to said other plane to automatically select an idle trunk in the 70 predetermined group.

96. In a telephone exchange repeater system, the combination of a plurality of trunks, a plurality of automatic switches, 75 means for controlling the operation of said switches by a varying number of impulses corresponding to the digits of the called number, each switch provided with a propelling mechanism, an actuating magnet for operating said propelling mechanism, 80 ground circuits including only one side of said trunks for energizing said magnets, a relay for successively controlling said circuits, means including two sides of the talking circuit in series for controlling said relay, and means for automatically extending 85 connection to said automatic switches.

97. In a telephone exchange repeater system, subscribers' lines, a plurality of first 90 selectors, each first selector provided with a line relay, trunks adapted to be automatically selected by said first selectors, other switches controlled by said relays over the trunks, by using the two sides of the latter separately in different ground circuits, 95 means for automatically selecting idle first selectors, said relays controlled over two sides of said subscribers' lines in series.

98. In an automatic telephone system, a 100 subscriber's line, a talking circuit including said line, an automatic switch for extending connection to a connector, and means for operating said connector to extend connection to a called line, means for automatically 105 ringing the called subscriber comprising a ringing relay, means for energizing said relay to throw ringing current on the called line, a ring cut-off relay, means for energizing said relay when the called subscriber answers to disconnect the ringing current from the called line and for locking said relay, a trunk release circuit for restoring the automatic apparatus when the subscribers are through talking and for restoring 110 the locking relay, said automatic switch operated over two sides of the talking circuit in series.

99. In an automatic telephone system, a 115 subscriber's line, a talking circuit including said line, an automatic switch for extending connection to a connector, and means for operating said connector to extend connection to a called line, means for automatically 120 ringing the called subscriber comprising a ringing relay, means for energizing said relay to throw ringing current on the called line, a ring cut-off relay, means for energizing said relay when the called subscriber answers to disconnect the ringing current from the called line and for locking said relay, a 125 130

trunk release circuit for restoring the automatic apparatus when the subscribers are through talking, and for restoring an automatic ringing apparatus to normal, said automatic switch operated over two sides of the talking circuit in series.

100. In a telephone system, automatic switching apparatus comprising a connector switch for connecting two lines, a ringer relay in said connector, an energizing circuit for said relay, an intermittent interrupter for controlling said circuit at one point, and a locking relay for controlling the circuit at another point, trunk release apparatus for restoring said switches and for restoring the circuit of the ringer relay to normal.

101. In an automatic telephone system, the combination with a pair of telephone lines connected for conversation, of a plurality of switches associated with said connected circuit, release relays at each of said switches, means to energize said release relays when the switches are taken for use, a pair of bridges across said circuit located at different switches, one or more intervening switches free from bridged electromagnets, the release of the switches depending upon the deenergization of their release relays, means whereby the bridge nearest the calling subscriber's station controls the release of all switches intervening between said switch and the switch containing the other bridge.

102. A telephone system including a calling subscriber's line and a called subscriber's line, a first selector switch, a second selector switch and a connector switch, each of said switches having motion in one plane to select groups of lines and motion in another plane to select idle lines in the selected groups of lines, switch adjusting magnets for each of said switches, a quick-acting line relay and a pair of slow-acting relays for said first selector switch, a normally at rest switching device responsive to the removal of the receiver at the calling substation to connect said calling subscriber's line to said first selector switch, and means responsive to current interruptions of the calling subscriber's metallic line circuit to operate said selector relays to directly transmit series of impulses to the switch adjusting magnets of the selector and connector switches to extend a connection from the calling subscriber's line to the called subscriber's line.

103. An automatic telephone system, comprising in combination, subscriber's lines, pre-selector, selector and connector switches, a repeater, one relay of said repeater having means for separating the calling and the called halves of the connection during the impulses, and means for energizing the said relay before the impulses start and until the impulses stop.

104. In a telephone system, a talking cir-

cuit, a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, and means including the two sides of the talking circuit in series for controlling said relay.

105. In a telephone system, a talking circuit, the combination of an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, means including the two sides of the talking circuit in series for controlling said relay, and an automatic switch mechanism allotted to and controlled by said relay.

106. In a telephone system, a talking circuit, the combination of a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including the two sides of the talking circuit in series for controlling said relay, and an automatic switch mechanism allotted to and controlled by said relay.

107. In a system having trunks divided into groups, a talking circuit, the combination of a plurality of automatic step-by-step trunk-selecting switches, each switch provided with a propelling mechanism and releasing mechanism, an actuating magnet for said propelling mechanism, circuits including trunk conductors for energizing said magnets, a relay for successively controlling said circuits, means including the two sides of the talking circuit in series for controlling said relay, and an automatic switch mechanism allotted to and directly controlled by said relay, said automatic switch mechanism having motion first in one plane to select a group and then motion in a plane at right-angles to said other plane to automatically select an idle trunk in the predetermined group, said releasing mechanism also controlled by said relay without operating said actuating magnets.

108. In a telephone system, a talking circuit, the combination of an automatic step-by-step switch, means for variably operating said switch in accordance with one or

- more digits of the called number comprising a magnet having its armature provided with means for directly actuating or propelling said switch, a circuit including a trunk conductor for energizing said magnet, a relay for controlling said circuit, means including the two sides of the talking circuit in series for controlling said relay, and means for automatically extending connection to said automatic switch. 109. In a telephone system, a talking circuit, the combination of a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including the two sides of the talking circuit in series for controlling said relay, and means for automatically extending connection to said automatic switches. 110. In a telephone system, a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including a metallic line circuit for controlling said relay, and means at the central station for supplying talking current over said metallic circuit. 111. In a telephone system, the combination of an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, and means at the central station for supplying talking current over said metallic circuit. 112. In a telephone system, the combination of a plurality of automatic switches, means for variably operating said switches in accordance with one or more digits of the called number, each switch provided with a propelling mechanism, an actuating magnet for propelling said mechanism circuits including trunk conductors for energizing said magnets, a relay for successively controlling said circuits, means including a metallic line circuit for controlling said relay, an automatic switch mechanism allotted to and controlled by said relay, and means at the central station for supplying talking current over said metallic circuit. 113. In a system having trunks divided into groups, the combination of a plurality of automatic step-by-step trunk-selecting switches, each switch provided with a propelling mechanism and a release mechanism, an actuating magnet for said propelling mechanism, circuits including trunk conductors for energizing said magnets, a relay for successively controlling said circuits, means including a metallic line circuit for controlling said relay, an automatic switch mechanism allotted to and directly controlled by said relay, said automatic switch mechanism having motion first in one plane to select a group and then motion in a plane at right-angles to said other plane to automatically select an idle trunk in the predetermined group, and means at the central station for supplying talking current over said metallic circuit, said release mechanism also controlled by said relay without operating said actuating magnets. 114. In a telephone system, the combination of an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, and means at the central station for supplying talking current over said metallic circuit. 115. In a telephone system, the combination of a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including a metallic line circuit for controlling said relay, means for automatically extending connection to said automatic switches, and means at the central station for supplying talking current over said metallic circuit. 116. In a telephone system, a talking circuit, an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, and means including the two sides of the talking circuit in series for

controlling said relay, the said energizing circuit including a ground connection controlled by said relay.

117. In a telephone system, a talking circuit, a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, and means including the two sides of the talking circuit in series for controlling said relay, the said energizing circuits including a ground connection controlled by said relay.

118. In a telephone system, a talking circuit, the combination of an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, means including the two sides of the talking circuit in series for controlling said relay, and an automatic switch mechanism allotted to and controlled by said relay, the said energizing circuit including a ground connection controlled by said relay.

119. In a telephone system, a talking circuit, the combination of a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including the two sides of the talking circuit in series for controlling said relay, and an automatic switch mechanism allotted to and controlled by said relay, the said energizing circuits including a ground connection controlled by said relay.

120. In a system having trunks divided into groups, a talking circuit, the combination of an automatic step-by-step switch, a magnet having its armature provided with means for directly actuating or propelling said switch, a circuit including a trunk conductor for energizing said magnet, a relay for controlling said circuit, means including the two sides of the talking circuit in series for controlling said relay, and an automatic switch mechanism allotted to and controlled by said relay, said automatic switch mechanism having motion first in one plane to select a group and then motion in a plane at right-angles to said other plane to automatically select an idle trunk in the predetermined group, the said energizing circuits including a ground connection controlled by said relay.

121. In a system having trunks divided into groups, a talking circuit, the combination of a plurality of automatic step-by-step trunk-selecting switches, each switch provided with a propelling mechanism and a release mechanism, an actuating magnet for said propelling mechanism, circuits including trunk conductors for energizing said magnets, a relay for successively controlling said circuits, means including the two sides of the talking circuit in series for controlling said relay, and an automatic switch mechanism allotted to and directly controlled by said relay, said automatic switch mechanism having motion first in one plane to select a group and then motion in a plane at right-angles to said other plane to automatically select an idle trunk in the predetermined group, the said energizing circuits including a ground connection controlled by said relay.

122. In a telephone system, a talking circuit, the combination of an automatic step-by-step switch, means for variably operating said switch in accordance with one or more digits of the called number comprising a magnet having its armature provided with means for directly actuating or propelling said switch, a circuit including a trunk conductor for energizing said magnet, a relay for controlling said circuit, means including the two sides of the talking circuit in series for controlling said relay, and means for automatically extending connection to said automatic switch, the said energizing circuit including a ground connection controlled by said relay.

123. In a telephone system, a talking circuit, the combination of a plurality of automatic switches, means for variably operating said switches in accordance with one or more digits of the called number, each switch provided with a propelling mechanism, an actuating magnet for propelling said mechanism, circuits including trunk conductors for energizing said magnets, a relay for successively controlling said circuits, means including the two sides of the talking circuit in series for controlling said relay, and means for automatically extending connection to said automatic switches, the said energizing circuits including a ground connection controlled by said relay.

124. In a telephone system, an automatic step-by-step switch, a magnet having its armature provided with means for directly actuating or propelling said switch, a circuit including a trunk conductor for energizing said magnet, a relay for controlling said circuit, means including a metallic line circuit

for controlling said relay, and a pair of voice-current trunk conductors between which said relay is permanently bridged.

125. In a telephone system a plurality of 5 automatic switches, each switch provided with a propelling mechanism and a release mechanism, an actuating magnet for said propelling mechanism, circuits including trunk conductors for energizing said magnets, a relay for successively controlling said 10 circuits, means including a metallic line circuit for controlling said relay, and a pair of voice-current trunk conductors between which said relay is permanently bridged, 15 said release mechanism also controlled by said relay without operating said actuating mechanism.

126. In a telephone system, the combination 20 of an automatic step-by-step switch, a magnet having its armature provided with means for directly actuating or propelling said switch, a circuit including a trunk conductor for energizing said magnet, a relay for controlling said circuit, means including 25 a metallic line circuit for controlling said relay, an automatic switch mechanism allotted to and controlled by said relay and a pair of voice-current conductors between which said relay is permanently bridged.

30 127. In a telephone system, the combination 35 of a plurality of automatic switches, each switch provided with a propelling mechanism and a release mechanism, an actuating magnet for said propelling mechanism, circuits including trunk conductors for energizing said magnets, a relay for successively controlling said circuits, means including a metallic line circuit for controlling said relay, an automatic switch mechanism allotted to and controlled by said relay, 40 and a pair of voice-current trunk conductors between which said relay is permanently bridged, said release mechanism also controlled by said relay without operating said actuating magnets.

45 128. In a system having trunks divided into groups, the combination of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a pair of voice-current trunk conductors between which said relay is permanently bridged.

50 129. In a system having trunks divided into groups, the combination of a plurality

of automatic switches, each switch provided with a propelling mechanism and a release mechanism, an actuating magnet for said propelling mechanism circuits including 70 trunk conductors for energizing said magnets, a relay for successively controlling said circuits, means including a metallic line circuit for controlling said relay, an automatic switch mechanism allotted to and controlled by said relay, said automatic switch mechanism having motion first in one plane to select a group and then motion in a plane at right-angles to said other plane to automatically select an idle trunk in the predetermined group, and a pair of voice-current 80 trunk conductors between which said relay is permanently bridged, said release mechanism also controlled by said relay without operating said actuating magnets.

130. In a telephone system, the combination 85 of an automatic step-by-step switch, a magnet having its armature provided with means for directly actuating or propelling said switch, a circuit including a trunk conductor for energizing said magnet, a relay for controlling said circuit, means including a metallic line circuit for controlling said relay, means for automatically extending connection to said automatic switch, and a pair of voice-current trunk conductors between which said relay is permanently 90 bridged.

131. In a telephone system, the combination 95 of a plurality of automatic switches, each switch provided with a propelling mechanism and a release mechanism, an actuating magnet for said propelling mechanism, circuits including trunk conductors for energizing said magnets, a relay successively controlling said circuits, means including 100 a metallic line circuit for controlling said relay, means for automatically extending connection to said automatic switches, and a pair of voice-current trunk conductors between which said relay is permanently 105 bridged, said release mechanism also controlled by said relay without operating said actuating magnets.

132. In a telephone system, an automatic 110 step-by-step switch, a magnet having its armature provided with means for directly actuating or propelling said switch, a circuit including a trunk conductor for energizing said magnet, a double-wound relay for controlling said circuit, means including a metallic line circuit for controlling said relay, and a pair of voice-current trunk conductors, one of said relay windings being 115 permanently connected to each of said conductors.

133. In a telephone system, a plurality of 120 automatic switches, each switch provided with a propelling mechanism, an actuating magnet for said propelling mechanism, circuits including trunk conductors for ener- 125

gizing said magnets, a double-wound relay for successively controlling said circuits, means including a metallic line circuit for controlling said relay, and a pair of voice-
5 current trunk conductors, one of said relay windings being permanently connected to each of said conductors.

134. In a telephone system, the combination of an automatic step-by-step switch, a
10 magnet having its armature provided with means for directly actuating or propelling said switch, a circuit including a trunk conductor for energizing said magnet, a double-wound relay for controlling said circuit,
15 means including a metallic line circuit for controlling said relay, an automatic switch mechanism allotted to and controlled by said relay, and a pair of voice-current trunk conductors, one of said relay windings being
20 permanently connected to each of said conductors.

135. In a telephone system, the combination of a plurality of automatic switches, each switch provided with a propelling
25 mechanism, an actuating magnet for said propelling mechanism, circuits including trunk conductors for energizing said magnets, a double-wound relay for successively controlling said circuits, means including a
30 metallic line circuit for controlling said relay, an automatic switch mechanism allotted to and controlled by said relay, and a pair of voice-current trunk conductors, one of said relay windings being permanently connected to each of said conductors.

136. In a system having trunks divided into groups, the combination of an automatic step-by-step switch, a magnet having its armature provided with means for directly
40 actuating or propelling said switch, a circuit including a trunk conductor for energizing said magnet, a double-wound relay for controlling said circuit, means including a metallic line circuit for controlling
45 said relay, an automatic switch mechanism allotted to and controlled by said relay, said automatic switch mechanism having motion first in one plane to select a group and then motion in a plane at right-angles to said
50 other plane to automatically select an idle trunk in the predetermined group, and a pair of voice-current trunk conductors, one of said relay windings being permanently connected to each of said conductors.

137. In a system having trunks divided into groups, the combination of a plurality of automatic switches, each switch provided with a propelling mechanism, an actuating magnet for said propelling mechanism, circuits including trunk conductors for energizing said magnets, a double-wound relay for successively controlling said circuits, means including a metallic line circuit for controlling said relay, an automatic switch
60 mechanism allotted to and controlled by said
65

relay, said automatic switch mechanism having motion first in one plane to select a group and then motion in a plane at right-angles to said other plane to automatically select an idle trunk in the predetermined group, and a pair of voice-current trunk conductors, one of said relay windings being permanently connected to each of said conductors.

138. In a telephone system, the combination of an automatic step-by-step switch, a magnet having its armature provided with means for directly actuating or propelling said switch, a circuit including a trunk conductor for energizing said magnet, a double-wound relay for controlling said circuit, means including a metallic line circuit for controlling said relay, means for automatically extending connection to said automatic switch, and a pair of voice-current trunk conductors, one of said relay windings being permanently connected to each of said conductors.

139. In a telephone system, the combination of a plurality of automatic switches, each switch provided with a propelling mechanism, an actuating magnet for said propelling mechanism, circuits including trunk conductors for energizing said magnets, a double-wound relay for successively controlling said circuits, means including a metallic line circuit for controlling said relay, means for automatically extending connection to said automatic switches, and a pair of voice-current trunk conductors, one of said relay windings being permanently connected to each of said conductors.

140. In a telephone system, a plurality of automatic switches responsive to different digits of the called number, only one of said switches being provided with line relays, one of said switches without relays completing the connection to the called line, and means for controlling the operation of said switches over two sides of a line circuit in series.

141. In a telephone system, a plurality of lines divided into groups, a selector switch having one motion to select groups and a second motion to connect with an idle line in a selected group, a line relay, a slow-acting relay, means for energizing said slow-acting relay, substation-controlled means for controlling the operation of said switch when said slow-acting relay is energized, means for operating said switch automatically when said slow-acting relay is deenergized, and means in said switch for repeating impulses over said selected line.

142. In a telephone system, a plurality of lines divided into groups, a selector switch having one motion to select groups and a second motion to connect with an idle line in a selected group, a line relay, a slow-acting relay, means for energizing said slow-

acting relay, substation-controlled means for controlling the operation of said switch when said slow-acting relay is energized, means for operating said switch automatically when said slow-acting relay is deenergized, and means in said switch for repeating impulses over a selected line.

143. In a telephone system, a plurality of lines divided into groups, a selector switch having one motion to select groups and a second motion to connect with a slow-acting relay, means for energizing said slow-acting relay, substation-controlled means for controlling the operation of said switch when said slow-acting relay is energized, means for operating said switch automatically when said slow-acting relay is deenergized, and means controlled by said line relay for repeating impulses over the selected line.

144. In a telephone system, a plurality of lines divided into groups, a selector switch having one motion to select groups and a second motion to connect with an idle line in a selected group, a line relay, a slow-acting relay, means for energizing said slow-acting relay, substation-controlled means for controlling the operation of said switch when said slow-acting relay is energized, means for operating said switch automatically when said slow-acting relay is deenergized, and means controlled by said line relay for repeating impulses over the selected line.

145. In a telephone exchange system, the combination of a calling subscriber's line, a called subscriber's line, means for interconnecting the lines including a first selector switch and a second selector switch, and means for releasing the second selector switch comprising a normally incomplete circuit and a relay provided with but a single energizing path arranged to complete said circuit when the first selector switch is released, said relay being energized during conversation over said lines.

146. In a telephone exchange system, the combination of a calling subscriber's line, a called subscriber's line, means for interconnecting the lines including a first selector switch and a second selector switch comprising a normally incomplete circuit containing a release magnet for the second selector switch, and a relay provided with but a single energizing path for completing said circuit when the first selector switch is released, said relay being energized during conversation over said lines.

147. In a telephone exchange system, the combination of a calling subscriber's line, means for interconnecting the lines including a first selector switch and a second selector switch, a relay associated with a second selector switch, a test conductor associated with the interconnecting means arranged to energize the relay when the first selector

switch selects a second selector switch, said relay being provided with but a single energizing path for controlling purposes, and means for releasing the second selector switch comprising a normally incomplete circuit, and means whereby said relay completes said circuit for rendering operable the releasing means of the second selector switch when the first selector switch is released.

148. In a telephone exchange system, the combination of calling subscribers' lines, called subscribers' lines, automatic switching mechanism for interconnecting the lines including first selector, second selector and connector switches, releasing means for said switches, test conductors for said switches, means for releasing the second selector switch by release of the first selector switch, said releasing means for the second selector switch comprising a relay provided with a single energizing path.

149. In a telephone exchange system, the combination of calling subscribers' lines, wanted subscribers' lines, automatic switching mechanism for interconnecting the lines including first selector, second selector and connector switches, release magnets associated with said switches, means for operating the release magnet of a second selector switch when the first selector switch associated therewith is released, said means comprising a relay provided with but a single winding and but two terminals, one terminal of said relay being connected directly to a source of current supply and the other terminal being accessible to the first selector switch.

150. In a telephone exchange system, the combination of calling subscribers' lines, wanted subscribers' lines, automatic switching mechanism for interconnecting the lines including first selector, second selector and connector switches, means for releasing the second selector switch comprising a relay provided with but a single energizing path and a release magnet, and means associated with the first selector switch for energizing and controlling said relay independent of the position of the second selector switch for controlling the release magnet of the second selector switch.

151. In a telephone exchange system, the combination of calling subscribers' lines, wanted subscribers' lines, automatic switching mechanism for interconnecting the lines including first selector, second selector and connector switches, means for releasing a second selector switch comprising a release magnet normally inactive, and means including a relay provided with but a single energizing path and for energizing said release magnet when the first selector switch associated with said second selector switch is released, said means being energized during conversation over said lines.

152. In a telephone exchange system, the combination of calling subscribers' lines, wanted subscribers' lines, automatic switching mechanism for interconnecting the lines including first selector, second selector and connector switches, means for releasing a first selector switch, means for releasing a second selector switch when said first selector switch releasing means is actuated, the releasing means for the second selector switch comprising a relay provided with a single energizing path and energized during the interconnection of said lines and deenergized upon the release of the first selector switch.
153. In a telephone exchange system, the combination of calling subscribers' lines, wanted subscribers' lines, automatic means for interconnecting said lines including first selector, second selector and connector switches, means for releasing a first selector switch, means for releasing the second selector switch comprising a relay provided with but a single energizing path, a release mag-

net maintained normally inactive by said relay, and means whereby said release magnet is actuated when the relay controlling the same is deenergized.

154. In a telephone exchange system, the combination of calling subscribers' lines, wanted subscribers' lines, automatic switching mechanism for interconnecting the lines including first selector, second selector and connector switches, and means for releasing a second selector switch comprising a relay provided with but a single energizing path energized when a first selector switch selects a link circuit terminating in a second selector switch, and a release magnet for said second selector switch rendered inactive when said relay is energized and rendered active to release said second selector switch when the first selector switch associated therewith is released.

Signed by me at Chicago, Cook County, Illinois, this 26th day of November, 1909.

BERNARD D. WILLIS.
